S. FREY

DISCHARGE SPOUT FOR LIQUID CONTAINERS

Filed Sept. 19, 1921

Inventor
Sigmund Frey.
By *you & your attys.*

UNITED STATES PATENT OFFICE.

SIGMUND FREY, OF LOS ANGELES, CALIFORNIA.

DISCHARGE SPOUT FOR LIQUID CONTAINERS.

Application filed September 19, 1921. Serial No. 501,713.

To all whom it may concern:

Be it known that I, SIGMUND FREY, a citizen of the United States, and a resident of Los Angeles, in the county of Los Angeles

5 and State of California have invented certain new and useful Improvements in Discharge Spouts for Liquid Containers, of which the following is a specification.

This invention relates to spouts of the 10 character employed on containers for liquid and it is especially serviceable for vessels containing extra supplies of water, gasoline, oil and the like for automobiles. The invention is also well adapted to be used in 15 connection with liquid measures of the character employed, for example, in measuring desired quantities of oil and discharging said oil into the crank case of an internal combustion engine. The invention is 20 not limited to the uses noted above, but is serviceable in connection with any container from which liquids are to be discharged.

An object of the invention is to provide a 25 discharge spout that can be neatly telescoped within the container, when not in use.

Another object is to provide a spout having a valve that is opened by pressing the container toward the vessel being supplied 30 with liquid from the container.

Another object is to provide a spout having a valve which is opened by pulling the container away from the vessel being supplied with liquid from the container.

35 The accompanying drawings illustrate several forms of the invention:

Figure 1 is a side elevation of a canteen with which one form of the invention is associated, a portion of the canteen being 40 broken away to show the spout telescoped within in closed position.

Figure 2 is an enlarged longitudinal section of the spout shown in Figure 1, a fragment of the canteen also being shown and 45 said canteen being turned on its side so as to bring the spout into horizontal position. The spout is shown drawn out ready for use, the valves being closed.

Figure 3 is a sectional view similar to 50 Figure 2, a portion of the discharge tube being broken away. The discharge tube is shown pulled outwardly to open one of the valves.

55 Figures 4 and 5 are sectional elevations on lines indicated by 4-4, 5-5, respectively, Figure 2.

Figure 6 is a sectional elevation on line indicated by 6-6, Figure 2, the parts rearward of the plane of section not being shown. 60

Figure 7 is a longitudinal section of a modified form of the invention, the spout being drawn out in discharge position and the discharge tube being pushed inwardly sufficiently to open one of the valves, a fragment of a liquid container also being shown. 65

Figure 8 is a front elevation of the spout tip shown in Figure 7.

Figure 9 is a longitudinal section of a still different form of the invention, the discharge tube being drawn out ready for use, 70 and a fragment of the liquid container also being shown.

Figure 10 is an inverted plan view of the tip of the spout in Figure 7. 75

The embodiments of the invention shown in Figures 1 to 8, inclusive, are alike in most respects, and the elements identical in both embodiments will first be described. A

liquid container is indicated at 10 and is 80 shown in Figure 1 in the form of a canteen provided with a handle 11 and with a cylindrical neck 12 surrounding an opening 13 formed in the top of the canteen. A detachable cap 14 normally closes the neck 12, 85 being, in this instance, screw-threaded upon said neck, as clearly shown in Figure 1. The wall of the opening 13 is screw-threaded as indicated at 15 to receive a screw-threaded annular flange 16 of a bushing 17. 90

The bushing 17 is provided with internal screw threads 18 in its inner end. Adapted to be engaged and disengaged with said screw threads 18 is the screw-threaded end 19 of a tubular valve or sleeve 20. Slid- 95

able through the bushing 17 is a discharge tube 21, in the embodiment of the invention shown in Figure 2 or a discharge tube 22 in the embodiment of the invention shown in Figure 7. The tube 21 or 22 is provided with a port or ports 23 which are normally closed by the sleeve 20 whether the tube is drawn into the extended position for use shown in Figure 2 or is telescoped within 100 the canteen as in Figure 1.

105 Connected to the sleeve 20 and forming an inward extension thereof is a valve cage 24 provided with longitudinal slots or ways 25 for the outer ends of a pin 26 which extends transversely through the tube 21 or 22, as the case may be. Loosely connected to the pin 26 is a longitudinally extending

stem 27 on which is slidably mounted a spring seat 28 and a valve plug 29 within the cage 24. Interposed between the spring seat 28 and valve plug 29 is a coil spring 30 which normally tends to hold the valve 29 against the inner open end 31 of the tube 21 or 22, as the case may be. This spring 30 also normally tends to hold the spring seat 28 against abutments 32 formed at the inner end of the valve cage 24. The stem 27 is provided with a shoulder 33 at its free end adapted to be engaged by the spring seat 28 so as to prevent said spring seat slipping off of the end of the stem 27 when the valve cage is pulled to the right as in Figure 3. The valve cage 24 is provided with an internal shoulder or shoulders 34 which are flush with the inner end of the discharge tube when the cage is in the position shown in Figure 2 with both valves closing the discharge tube. The shoulders 34 function to move the valve 29 away from the open tube end 31 to the position shown in Figure 3, against the expansive force of the spring 30, when the tube 21 is pulled out to the position shown in Figure 3, thus opening the valve 29 so as to permit the passage of liquid from the container into the open end 31 of the discharge tube.

30 The tube 21 is provided at its outer end with a bent tip 35 extending substantially at a right angle to the other portion of the tube, and to insure against collapse of said tip, when pressure is brought to bear against the tip to open the valve, there is inserted in said tip an angular member 36 which may be secured in place by any suitable means, for example, by a transversely extending rivet 37.

40 The discharge tube 22 is provided near its outer end with a discharge orifice 38 and a solid tip or cap 39 prevents discharge of liquid at the end of the nozzle. The tip 39 is provided with a forked portion 40 adapted to engage over the rim of a filling neck, such as that indicated at A in Figure 7. The fork 40, when thus engaged with the filling neck, holds the tube 22 against endwise movement when the container, with which the spout is associated, is pushed toward or from the filling neck A. The outermost branch of the fork 40 is preferably V-shaped in cross section so as to prevent slipping of the fork around the neck when the container is pulled away from said neck.

60 In the form of the invention illustrated in Figure 7, the bushing 17 is provided in its outer end with internal screw threads 41 adapted to receive the screw-threaded plug 42 formed by the cap 39. When the plug 42 is screwed into the threaded portion 41, the inner end of said plug seats against a packing washer 43 so as to absolutely prevent the leaking of liquid between

the tube 22 and the bushing 17 when the tube is in closed position within the container. The provision of the elements 41, 42 and 43 is especially serviceable if the spout is attached to the side of the container so that the spout is constantly in a substantially horizontal position, as it might be in some installations.

To use the form of the invention shown in Figures 1 to 6, the following procedure is carried out: Assuming that the parts are in the positions shown in Figure 1, with the tube 21 telescoped within the canteen and the cap 14 in place on the neck 12, said cap 14 will be unscrewed and removed from the neck. Then the tip of the tube 21 will be grasped by the operator and pulled out until the resistance of the spring 30 is encountered. Such resistance assures the operator that the spout is in extended position with the sleeve 20 against the bushing 17. The tube will then be turned to connect the sleeve and bushing.

The tip 35 is then inserted in the filling neck of the vessel into which it is desired to discharge liquid from the container, and the operator will either move the canteen 10 toward or from such filling neck, the tip 35 holding the spout against endwise movement while the canteen is thus moved. If the operator pulls the canteen away from the filling neck, the valve 29 will be caused to leave the open end 31 of the tube 21 so as to permit liquid to flow from the canteen into the spout and discharge from said spout. This open position of the tube is shown in Figure 3 of the drawings. If the operator pushes the canteen toward the filling neck, the tube holds the valve 29 while the sleeve 19 moves toward the tip of the tube against the pressure of the spring 30, and the ports 23 will thus be moved into open position beyond the inner end of the valve 20 so that liquid can flow from the canteen through the ports 23 into the tube. The positions of the parts just described, to open the ports 23, are clearly shown in Figure 7 of the drawings, and it will be readily understood that the embodiment of the invention shown in Figure 7 operates the same as that shown in Figures 1 to 6, excepting that the engagement of the tip 39 of the tube 22 with the filling neck A is a little different. In Figure 7, the discharge orifice 38 is above the level of the top of the filling neck A, thus enabling the operator to see the liquid discharge from the spout. The fork 40 will embrace the rim of the filling neck A so as to hold the spout 22 against endwise movement when the operator pushes the container toward or from the filling neck A.

Now referring to Figure 9 of the drawings, showing a valveless form of the invention, the liquid container is indicated at 44 and is provided with an opening 45 to

receive a bushing 46. The bushing 46 may be secured in the opening by solder or any other fastening means, and the inner end of the bushing 46 is provided with internal 5 screw threads 47 adapted to be engaged by a screw-threaded head 48 at the inner end of a discharge tube 49 which slides through the bushing 47 into closed position inside of the canteen or into extended position for 10 use as shown in the drawing. The screw threads 47, 48 constitute one form of cooperating means having a positive engagement for releasably holding the tube 49. Surrounding the opening 45 is a screw-threaded neck 50 on the container 44 adapted 15 to receive a cap, not shown, similar to the cap 14 shown in Figure 1 of the drawings, said cap being adapted to normally close the neck 50 when the spout 49 is shoved into the container. The tip of the nozzle 49 is provided with a shoulder 51 which enables one to more readily draw the tube 49 into 20 open position. The shoulder 51, when the tube is pushed into closed position, engages 25 the outer end of a coil spring 52 which surrounds the tube 49 and which is secured at its inner end to the outer end of the bushing 46. The spring 52 is compressed by pushing the tube 49 inwardly until its outer end 30 is within the neck 50, and the function of the spring is to push the tip of the tube 49 out of the neck 50 when the cap, not shown, is removed from the neck 50, thus enabling the operator to the more easily grasp the tube 35 to extend it into position for use.

In the form of the invention shown in Figure 9, the tube 49 will be drawn out sufficiently far to engage the head 48 with the inner end of the bushing 46, and the 40 tube will then be rotated to engage the screw threads of the head and bushing so as to hold the tube in open position. When the operator has finished discharging liquid from the container, he will turn the tube 49 to release 45 the head 49 from the bushing and he will then push the tube inwardly and apply the cap, not shown, to the neck 50 so as to prevent the discharge of liquid from and the entrance of dust to the container. When the 50 cap is in place, the container may be placed in any position without the contents discharging therefrom.

It is to be understood that any other cooperating releasable connecting means than 55 screw-threads for holding the discharge tube extended may be provided between the bushing 17 and sleeve 20 and also between the bushing 46 and the head 48.

I claim:

60 1. The combination with a liquid container, of a bushing in the wall of the container, a tube of uniform outside diameter closely fitting the bore of the bushing and 65 slideable therein, and having means at its inner end to engage the bushing to limit

outward movement of the tube, the container having a neck surrounding the tube, said means and bushing being interlocking when the tube is extended, and a cap to close said neck. 70

2. The combination with a liquid container, of a bushing in the wall of the container, and a tube slideable in the bushing, the inner ends of the bushing and tube being provided with cooperating means having a positive engagement to releasably hold the tube extended. 75

3. The combination with a liquid container, of a bushing in the wall of the container, a tube slideable in the bushing, a pin 80 carried by the inner end of the tube, a valve cage surrounding the inner end of the tube and having internal shoulders, a valve plug in the cage prevented from outward movement by the shoulders, a stem connected with 85 the pin and slideable in the valve plug and provided with an abutment on its free end, a spring seat on the stem, and a spring between the spring seat and the valve plug. 90

4. The combination with a liquid container, of a bushing in the wall of the container, a tube slideable in the bushing and having a port, a sleeve surrounding the tube and closing the port when the sleeve is in one position, cooperating means releasably connecting the sleeve and bushing, means 95 yieldingly holding the sleeve in port closing position, and a closure for the inner end of the tube. 100

5. The combination with a liquid container, of a bushing in the wall of the container, a tube slideable in the bushing and having a port, a sleeve surrounding the tube, a valve to close one end of the tube, means 105 yieldingly holding the sleeve in position to close the port and yieldingly holding the valve in closed position, and means connected with the sleeve and engaging the valve to open it when the sleeve is moved toward the valve. 110

6. The combination with a liquid container, of a bushing in the wall of the container, a tube slideable in the bushing and having a port, a sleeve surrounding the tube, cooperating means releasably connecting the sleeve and bushing, a valve to close one end of the tube, means 115 yieldingly holding the sleeve in position to close the port and yieldingly holding the valve in closed position, and means connected with the sleeve and engaging the valve to open it when the sleeve is moved toward the valve. 120

7. The combination with a liquid container, of a discharge tube movably connected with the container, and valve means operated by endwise movement of the tube in either direction to admit liquid from the container to the tube. 125

8. The combination with a liquid container, of a discharge tube mounted to slide 130

- into the container, and valve means operative by endwise movement of the tube in either direction to admit liquid from the container to the tube.
9. The combination with a container, of a discharge tube for the container provided with means at its tip to engage the filling neck of a vessel, valve means operated into open position by movement of the container away from the filling neck when the tube engages said neck, and means tending to hold the valve means in closed position.
10. The combination with a container, of a discharge tube for the container provided with means at its tip to engage the filling neck of a vessel, valve means operated into open position by movement of the container toward the filling neck when the tube engages said neck, and means tending to hold the valve means in closed position.
11. The combination with a container, of a discharge tube for the container provided
- with means at its tip to engage the filling neck of a vessel, valve means operated into open position by movement of the container toward and from the filling neck when the tube engages said neck, and means tending to hold the valve means in closed position.
12. The combination with a liquid container, of a tube movably associated with the container and having a tip engageable with the filling opening of a vessel, means normally closing the tube against the entrance of liquid from the container, and means operative by moving the container when the tube is engaged with the filling opening to open the tube-closing means.

Signed at Los Angeles, California, his 2d day of September, 1921.

SIGMUND FREY.
